(57) **CLAIM**

The ornamental design for a switch, as shown and described.

DESCRIPTION

FIG. 1 is a perspective view of an embodiment of the ornamental design of a switch.

FIG. 2 is a front view of an embodiment of the ornamental design of the switch.

FIG. 3 is a back view of an embodiment of the ornamental design of the switch.

FIG. 4 is a top view of an embodiment of the ornamental design of the switch.

FIG. 5 is a bottom view of an embodiment of the ornamental design of the switch.

FIG. 6 is a side view of an embodiment of the ornamental design of the switch.

FIG. 7 is a perspective view of an embodiment of the ornamental design of the switch.

FIG. 8 is a front view of an embodiment of the ornamental design of the switch.

FIG. 9 is a back view of an embodiment of the ornamental design of the switch.

FIG. 10 is a top view of an embodiment of the ornamental design of the switch.

FIG. 11 is a bottom view of an embodiment of the ornamental design of the switch; and,

FIG. 12 is a side view of an embodiment of the ornamental design of the switch.

The broken-line disclosure in the views is understood to represent portions of the article in which the claimed design is embodied, but which form no part of the claimed design.

1 Claim, 10 Drawing Sheets
